HEEL-ATTACHING MACHINE

George W. Freeman, Swampscott, Mass., assignor
to United Shoe Machinery Corporation, Paterson, N. J., a corporation of New Jersey

Application December 13, 1934, Serial No. 757,343

17 Claims. (Cl. 1—32)

My invention relates to machines for attaching heels to shoes, it being particularly adapted to operate upon that type of shoe, commonly called a mule, which is without a counter- or 5 quarter-portion.

In the heelng of shoes, the operating position, upon the work-supporting jack of a machine arranged for inside-nailing, is commonly determined by a gage member carried by the jack itself and contacting with the inside of the counter-portions of the shoes. I provide means by which work having no rear portion to the upper may be accurately located for the heelng operation and without interference with the delivery to 10 the jack of the nails or other fastenings by which the attachment of the heels is to be effected. In attaining this end, I combine in a novel manner with a jack, or like work-support, transferring means for fastenings, this being shown 15 herein as a nail-loader, and gaging or work-positioning means normally lying in the path of the transferring means and being movable in the operation of the machine out of said path, this movement preferably being effected by the transferring means itself. This permits the gaging means to be so located with relation to the jack that shoes without rear portions may be positioned effectively for the operation upon them, and then said gaging means automatically dis- 20 placed so the fastening-delivery may be made without interference. Gages are preferably provided for both a sole and a heel, they being arranged to move together into and out of co-operation with the jack, and being so arranged 25 that they may be fixed individually in different positions to change the relation of the work-pieces to the points of insertion of the fastenings and to each other. In such a double organization, there is believed to be patentable novelty, 30 regardless of the manner in which the gaging means is moved and the purpose of its movement. In the illustrated apparatus is included a jack supported upon the machine-frame, a carrier movable upon the frame, a gage for work sup- 35 ported upon the jack, said gage being mounted upon the carrier, and a spring acting upon the carrier and holding the gage yieldably in co-operation with the jack. The force of the spring may be utilized, not only to urge the gage means 40 into co-operation with the jack but also out of co-operation therewith. This allows the gage to be displaced from active position, as under the influence of the reciprocating nail-loader, and also to be held in an inactive position by the 45 same spring.

A particular embodiment of the invention is shown in the accompanying drawings,

Fig. 1 being a broken side elevation of the essential parts of my improved machine;

Fig. 2, a similar view, the gaging means being 5 indicated in other positions than in Fig. 1;

Fig. 3, a broken front elevation; and

Fig. 4, a horizontal section taken above the jack and loader and with the work removed from the former.

The invention is disclosed herein in connection with such a heelng machine as that of Letters Patent of the United States No. 1,785,928, Benjamin, December 23, 1930. A fragment of the frame appears at 10. Upon this are mounted 15 a work-supporting jack 12 fixed against movement and in which operates nail or other fastening-inserting mechanism 14; a vertically movable pressure-abutment 16 for holding the work in place upon the jack during the insertion of 20 the nails by the mechanism 14; and a reciprocatory transferring or loading mechanism 18, which may receive nails from tubes 20 and deliver them to nail-passages 22 in the jack 12. When the machine is employed for the heelng 25 of shoes having the usual counter- or quarter-portions, they are located in the correct relation to the passages 22, and therefore to the points of insertion of the nails, by contact of such portion with a gage member 24 adjustable 30 in position forwardly and rearwardly upon the jack. The mule-type of shoe, however, has nothing which may make this contact with the jack-gage, and heretofore the proper location of such work has been left to the uncertain judgment 35 of the operator. The heel to be attached may also lack means for locating it, as when there is no breast-cut in the sole, and the heel is not to be attached fully back to the rear of the sole. By my invention I provide for the correct 40 positioning of both a quarterless shoe and its heel for the nailing operation, and the positioning means, though rising above the jack-top, is kept clear of the path of the loader 18.

At one side of the frame 10 a bracket 26 is 45 secured, this having fixed near its lower extremity a horizontal stud 28. Mounted to oscillate about the stud is a carrier 30, having extending inwardly toward the rear of the jack 12 an arm 32. At the end of the arm is an extension 34 provided with a rib 36 entering a slot in the shank 38 of a fork 40, furnishing a gage for the rear of the insole I of a mule M, portions of the outsole and upper of which appear at S and U, respectively. As is best seen in Fig. 4 of 50 55

the drawings, the fork at opposite sides of the rear of the insole will so engage it that this portion of the shoe is located laterally as well as longitudinally. A slot-and-screw connection 42 5 joins the shank of the fork to the arm-extension 34, permitting said fork to be adjusted forwardly and rearwardly, so the point or points of insertion of the nail or nails N used for the attachment of a heel H to the sole may be varied. 10 In work of the class now under consideration, the operator commonly locates the heel upon the insole by touch, guided by coincidence between the curved periphery of the heel and that of the heel-seat-portion of the insole. This is 15 at best inexact, and fails under certain conditions, as when the periphery of the heel is to be situated inwardly from that of the insole. This may be the case when it is desired to show a line of ornamental stitching about the margin 20 of said insole. By my invention the relation of the heel to the insole is made certain by a gage-fork 44. The upper central portion of the sole-fork 40 is shown (Fig. 3) as grooved longitudinally to receive a rib 46 in the under side of 25 the shank 48 of the fork 44. A slot-and-screw connection 50 between the shanks of the two forks allows the heel-gage to be so set with relation to the sole-gage along a substantially horizontal plane that the heel may be located 30 either with its periphery and that of the sole in registration, or so that the desired amount of margin of the latter may be exposed.

The gages may be maintained either in active position, as shown in Fig. 1 of the drawings, 35 when such work as the heeling of mules is to be performed, or in inactive position, as represented by dash-lines in Fig. 2, in connection with regular work when the jack-gage 24 may be utilized. This I may accomplish by a single 40 set of connections between the carrier 30 and a relatively fixed point, as the bracket 26. In the bracket is a horizontal bore receiving the shank 52 of a block 54, which, by this mounting, is 45 permitted to rock. Through a bore in the block is movable longitudinally a rod or link 56 pivoted at 58 to an arm 60 of the carrier 30. Surrounding the rod is a helical spring 62 bearing at its opposite extremities against an enlargement 64 of the rod and against the block 54. 50 This forces the arm 60 downwardly to an extent determined by contact with the block of locked nuts 66 threaded upon the upper extremity of the rod. When the gages are in the active position, as illustrated in Fig. 1, the rod and spring 55 lie at one side of a line joining the axes of the stud 28 and the block-shank 52, holding the gages yieldably in place. At this time, the angular relation of the gages to the top of the jack may be adjusted by the nuts 66 to bring 60 said gages into the proper positions in a vertical plane. When the present gaging mechanism is not to be employed, the carrier 30 is turned manually in an anticlockwise direction (Fig. 1) until the rod passes the previously indicated 65 center-line. Now the parts will assume the positions indicated in dash-lines in Fig. 2, the gages being clear of the jack and so held, close to the frame, by the spring 62.

In delivering nails to the jack 12, the loader 70 70 travels above the jack-top and in close proximity to it. Were the gage-forks 40 and 44 left in their active gaging positions, interference would be produced. I therefore cause their withdrawal from the path of the loader, this, 75 as herein disclosed, being as an incident to the

operation of the machine. In a vertical wall of the loader-slide of the Benjamin apparatus, already referred to, is a longitudinal horizontal slot 70 which receives guiding means fixed to the frame 10. At the forward extremity of the upper wall 72 of this slot is an inwardly and downwardly inclined surface 74. Upon the gage-carrier 30 I mount a roll 76, which, when the gage mechanism is in active position, is horizontally aligned with this surface 74. Consequently, as 10 the loader advances toward the jack, said surface strikes the roll, moving it and the carrier downwardly and rearwardly to the position appearing in full lines in Fig. 2, before any part of the loader encounters elements of the gage mechanism which otherwise would lie in its path. The loader may thus function without interference from said mechanism. This temporarily inactive relation of the forks is maintained, as long as the loader is forward, by the 15 engagement of the roll 76 with the slot-surface 72. When the loader retreats to its nail-receiving position, the spring 62 returns the gage mechanism to normal.

In using, for mule or like counterless work, heel-attaching machines equipped with the gages of this invention, the operator may, by the nuts 66, adjust the fork 40 to the correct vertical relation to the top of the jack 12, and by the slot-and-screw connection 42 so secure said fork 30 horizontally that nails N driven by the mechanism 14 will be properly located in the soles I and S. By the slot-and-screw connection 50 the fork 44 may be positioned to determine the relation of the periphery of the heel H to that of the 35 heel-seat-portion of the insole. Initially, the forks are held by the spring 62 as appears in Fig. 1, ready for the gaging action. With the shoe and heel ready for application to the jack, the operator causes the loader 18 to deliver the 40 nails which it carries to the jack-passages 22. The loader-slide-surfaces 74 and 72, by successive engagement with the carrier-roll 76, cam down and then hold the gage-forks and their supporting elements below the path of the loader; see the 45 full-line-position in Fig. 2. Upon the return of the loader to its initial position, the spring 62 raises the forks, and the operator may at once 50 jack the shoe and place upon it the heel under the guidance of said forks. The abutment 16 is thereupon lowered to clamp the work and power-operation of the machine produced to cause the mechanism 14 to insert the nails through the 55 insole and outsole into the heel. The completed work may now be removed from the jack. If, because of regular work with uppers having counter-portions, the gage 24 rather than the forks is to be employed, the forks and their 60 supporting elements are swung down entirely clear of the jack and loader, as indicated in dash-lines in Fig. 2, where it is retained by the spring 62 which has crossed the center of the carrier-pivot.

Having described my invention, what I claim as new and desire to secure by Letters Patent of 65 the United States is:

1. The combination with a shoe-support, of transferring means movable to deliver fastenings to the support, work-positioning means co-operating with the support, said positioning means normally lying in the path of the transferring means and being movable in the operation of the machine below said path, and a spring for elevating the positioning means into said path.

2. The combination with a shoe-support, of 75

- transferring means movable to deliver fastenings to the support, work-positioning means co-operating with the support, said positioning means normally lying in the path of the transferring means and being movable in the operation of the machine out of said path, and a spring effective to urge the positioning means both toward and away from said path.
3. In a heel-attaching machine, a jack, a work-gage pivoted to swing from a position in active co-operation with the jack downwardly and rearwardly therefrom, and a nail-loader delivering to the jack and acting upon the gage to turn it about its pivot.
- 10 4. In a heel-attaching machine, a jack, a work-gage pivoted to swing from a position in active co-operation with the jack downwardly and rearwardly therefrom, means arranged to locate the gage in different active positions, and a nail-loader delivering to the jack and acting upon the gage to turn it thus located.
- 15 5. In a heel-attaching machine, a jack, a work-gage pivoted to swing from a position in active co-operation with the jack downwardly and rearwardly therefrom, means arranged to locate the gage in different active positions in a substantially vertical plane, and a nail-loader delivering to the jack and acting upon the gage to turn it out of the position in which it is thus located.
- 20 6. In a heel-attaching machine, a jack, a work-gage pivoted to swing from a position in active co-operation with the jack downwardly and rearwardly therefrom, means arranged to locate the gage in different active positions in a substantially horizontal plane, and a nail-loader delivering to the jack and acting upon the gage to turn it out of the position in which it is thus located.
- 25 7. In a heel-attaching machine, a jack, a work-gage movable into and out of active co-operation with the jack, and a spring acting to force the gage in both directions.
- 30 8. In a heel-attaching machine, a jack, a work-gage movable into and out of active co-operation with the jack, a spring effective to force the gage in both directions, and a nail-loader delivering to the jack and acting upon the gage to move it against the force of the spring.
- 35 9. In a heel-attaching machine, a jack, a gage arranged for contact with the sole of a jacked shoe, a gage arranged for contact with a heel upon the heel-seat of the jacked shoe, said gages being movable together into and out of position for contact with the sole and heel respectively, and means arranged to fix the gages individually in different positions for their respective contact with the work.
- 40 10. In a heel-attaching machine for mule-work, a jack, and a sole-gage movable in the operation of the machine from a position just at the rear of the jack-top downwardly therefrom.
- 45 11. In a heel-attaching machine for mule-work, a jack, and a sole-gage and a heel-gage movable together in the operation of the machine from a position just at the rear of the jack-top downwardly therefrom.
- 50 12. In a heel-attaching machine, a frame, a jack supported upon the frame, a carrier movable upon said frame, a gage for work supported upon the jack, said gage being mounted upon the carrier, a link pivoted to the carrier and guided upon the frame, and a spring surrounding the link and acting upon the carrier.
- 55 13. In a heel-attaching machine, a frame, a jack supported upon the frame, a carrier movable upon said frame, a gage for work supported upon the jack, said gage being mounted upon the carrier, a link pivoted to the carrier and guided upon the frame, a spring surrounding the link and acting upon the carrier, and means arranged to vary the extent of movement of the link under the influence of the spring.
- 60 14. In a heel-attaching machine, a frame, a jack supported upon the frame, a carrier movable upon said frame, a gage for work supported upon the jack, said gage being mounted upon the carrier, and a spring acting upon the carrier and holding the gage alternatively in active co-operation with the jack and out of co-operation therewith.
- 65 15. In a heel-attaching machine, a frame, a jack supported upon the frame, a carrier movable upon said frame, a gage for work supported upon the jack, said gage being mounted upon the carrier, a spring acting upon the carrier and holding the gage yieldably in co-operation with the jack, and a reciprocating nail-loader having a surface extending in the direction of reciprocation and a surface inclined thereto, the inclined surface and associated surface successively engaging the carrier.
- 70 16. In a heel-attaching machine for mule-work, a frame, a jack supported thereon, a carrier movable upon the frame, a sole-fork mounted upon the carrier, means arranged to fix the sole-fork upon the carrier in different positions toward and from the jack, a heel-fork mounted upon the sole-fork, and means arranged to fix the heel-fork in different positions upon the sole-fork toward and from the jack.
- 75 17. In a heel-attaching machine for mule-work, a frame, a jack supported thereon, a carrier pivoted upon the frame to move vertically, a gage-fork mounted upon the carrier and co-operating with the jack, and means arranged to carry the normal position of the carrier vertically about its pivot.

GEORGE W. FREEMAN.
